SYDNEY NORTON BARUCH, OF SAN FRANCISCO, CALIFORNIA.

APPARATUS FOR PRODUCING THERAPEUTICAL EFFECTS.

1,425,743.

Specification of Letters Patent. Patented Aug. 15, 1922.

Application filed May 14, 1919. Serial No. 297,102.

To all whom it may concern:

Be it known that I, SYDNEY NORTON BARUCH, a citizen of the United States, and a resident of the city and county of

6 San Francisco, State of California, have invented a certain new and useful Apparatus for Producing Therapeutical Effects, of which the following is a specification.

The invention relates to a process of producing therapeutic effects and to an apparatus for carrying out such process.

An object of the invention is to provide an apparatus for producing dielectric or electrostatic hysteresis within the body.

15 Another object of the invention is to produce an alternating electrostatic field of a plurality of different frequencies, whereby a heterodyne effect is produced.

The loss of power in the dielectric in an 20 alternating current electrostatic field consists of two distinctly different components, of which one is directly proportional to the frequency (analogous to magnetic hysteresis) and thus a constant loss of energy per 25 cycle, independent of the frequency, while the other component is proportional to the square of the frequency (analogous to the loss of power by eddy currents) and thus a loss of energy per cycle proportional to the 30 frequency. The first loss is probably true dielectric static hysteresis and the second loss is the viscous component of dielectric hysteresis. If the loss of power by electrostatic hysteresis is proportional to the square 35 of the frequency and of the field intensity, then it is proportional to the square of the electromotive force. In the apparatus of my invention I have provided means for producing a plurality of different frequencies and also for interrupting the various 40 frequencies at different times, so that a rapidly varying frequency is produced. In one form of apparatus which I have constructed and which is producing remarkable 45 therapeutic effects, particularly in the reduction of blood pressure, the frequencies are varied from 60 cycles (alternating current supply) up to radio frequency. Since the dielectric hysteresis constitutes

50 a power loss, this power is consumed in the dielectric and the greater the electrostatic losses, the greater will be the effect produced in the dielectric. The current which I employ is a high potential current and the 55 frequencies are high, so that the power con-

sumed in the dielectric is great and due to the presence of different frequencies at the same time, remarkable therapeutic effects are produced.

In accordance with my invention, I place 60 the body of the patient being treated in the electrostatic field, so that the body forms the dielectric and the electrostatic hysteresis losses occur therein. I am not aware of all of the physical or therapeutical effects 65 which flow from the subjection of the body to the varied and changing frequency field, but it operates to increase to a degree the general metabolism by inducing functional activity. This activity is apparently manifested throughout the whole body, increasing the elimination of solids and carbon dioxide throughout the body and also producing marked effects upon general nutrition. 75

The invention possesses other advantageous features, some of which, with the foregoing, will be set forth at length in the following description where I shall outline in full that form of the apparatus which I 80 have selected for illustration in the drawing accompanying and forming part of the present specification. In said drawing I have shown one form of the apparatus of my invention, but it is to be understood that 85 I do not limit myself to such form, since the invention as set forth in the claims, may be embodied in a plurality of forms.

The drawing is a diagrammatic representation of the apparatus of my invention. 90

The process of my invention consists in producing electrostatic hysteresis losses in the body by placing it in an electrostatic field of varying frequency or of a plurality 95 of frequencies whereby a heterodyne effect is produced. This is accomplished by placing the body between the plates of a condenser which are connected in circuit in which currents of different frequencies are produced. When applied to the body for effecting the reduction of high blood pressure I am of the opinion that the effect of the electrostatic hysteresis is to induce local currents in the body and these currents assist in freeing the calcium sulphate which has formed or been deposited in the walls of the arteries. The process of reducing blood pressure consists of a series of treatments or subjections of the body to the multi-frequency electrostatic field and during the period in which 110

the treatments are given, the person should eat no substances containing salts which have a tendency to produce calcium sulphate. Also during the period of the treatment the person should partake of magnesium chloride in prescribed doses. The magnesium chloride combines with the freed calcium sulphate to produce calcium chloride and magnesium sulphate both of which are soluble in the small quantities in which they are present.

The apparatus of my invention comprises a wireless transformer 3, the primary 4 of which is connected to the alternating current supply mains. An adjustable choke coil 5 is arranged in one lead of the primary, so that the current flow to the transformer may be controlled. Connected across the secondary 6 of the transformer, is an interrupter, preferably a rotary spark gap device. In the present construction I have employed two rotary spark gap devices 12—13, connected in parallel, with the electrodes on one rotary element staggered with relation to the electrodes of the other element, so that a frequency of interruption of double the interruption frequency of one element is produced. Connected across the interrupter is a high frequency oscillatory circuit containing the condenser 7 and the inductance coil 9, which is preferably large in diameter and composed of a few turns.

In one apparatus which I have constructed, the frequency of interruption of the condenser-inductance circuit is 900 per second, but I do not limit myself to any specific interruption frequency. As the rotating element of the interrupter rotates, there are periods of no spark, in which the inductance circuit is open, there are periods of very short spark, when the electrodes are in their closest positions, and there are periods when long sparks are drawn, due to the ionization of the air in the spark gap. During the second period, current of the line frequency is produced in the inductance and as the sparks are drawn out into the third period, the frequency and potential increases. There is therefore produced in the inductance, a plurality of different frequencies, ranging from the line frequency, through the interrupter frequency to radio frequency or other high frequency.

Connected to the side of the inductance coil 9 adjacent the interrupter is a secondary inductance coil 14, which is also inductively coupled with the coil 9. The coil 14 is provided with a large number of turns of smaller diameter than the coil 9 and is preferably arranged axially with respect to the large coil. The other end of the coil 14 is connected to a condenser plate 15 and the other condenser plate 16 is connected to the juncture of the two inductance coils. The plate 16 is covered with suitable insulation

and the patient lies directly over such plate, being insulated therefrom. The plate 15 is preferably in the form of a flexible screen, covered with insulation material and is placed over the patient, resting on him. 70 The body of the patient thereby forms the condenser dielectric, in which the dielectric hysteresis losses due to the multi-frequency current occur.

I claim:

1. A therapeutic apparatus of the character described comprising a pair of condenser plates, a secondary induction coil connected at its opposite ends to said plates, a primary induction coil inductively connected to said secondary coil and means for producing a plurality of high frequency currents out of phase with each other in said coils. 80

2. A therapeutic apparatus of the character described comprising a pair of condenser plates, a secondary induction coil connected at its opposite ends to said plates, a primary induction coil inductively connected to said secondary coil and means for producing a plurality of interrupted high frequency currents out of phase with each other in the coils. 90

3. A therapeutic apparatus of the character described comprising a pair of condenser plates, a secondary induction coil connected at its opposite ends to said plates, a primary induction coil inductively connected to said secondary coil and means for producing a plurality of currents of different frequencies in the primary coil. 95

4. A therapeutic apparatus of the character described comprising a pair of condenser plates, a secondary induction coil connected at its opposite ends to said plates, a primary induction coil directly and inductively connected to said secondary coil, a source of alternating current of high potential, interruptors, connected out of step with each other across said source, a circuit containing said primary coil in parallel with the interruptors, and a condenser in said circuit. 105

5. An apparatus of the character described comprising a pair of condenser plates, a secondary induction coil connected at its opposite ends to said plates, a primary induction coil directly and inductively connected to said secondary coil, a source of alternating current of high potential, a plurality of rotary spark gap devices connected in parallel and connected across said source out of step with each other, a circuit containing said primary coil in parallel with the devices and a condenser in said circuit. 115

6. A therapeutic device comprising a transformer, a pair of condenser plates for application to the human body, and means electrically interposed between said transformer and said condenser plates for con- 125

verting the voltage of said transformer into an intermittent voltage of a varying frequency and for impressing said intermittent voltage on the said condenser plates.

5 7. A therapeutic device comprising a pair of condenser plates, lead wires adapted to be connected to a source of voltage, and means electrically interposed between said plates and said wires for converting the voltage of 10 said source into a voltage of a plurality of frequencies out of phase with each other and for impressing said last named voltage on the said plates.

8. A therapeutic device comprising means 15 for connecting said device to a source of voltage, means for converting said voltage into a voltage of a plurality of frequencies out of phase with each other, and means for applying said last named voltage to the 20 human body.

9. A therapeutic device comprising means for connecting said device to a source of current, means for converting said current into a current of a plurality of high frequencies out of phase with each other, and 25

means for conducting said last named current to the human body.

10. A therapeutic device comprising a pair of condenser plates, means for connecting said device to a source of current, and means 30 electrically interposed between the said plates and the first named means for converting the current of the said source into a current of a plurality of frequencies out of phase with each other. 35

11. A therapeutic device comprising a transformer, a pair of condenser plates for application to the human body, and means electrically interposed between said transformer and said condenser plates for converting the transformer current into an intermittent current of varying high frequencies. 40

In testimony whereof, I have hereunto set my hand at San Francisco, California, 45 this 24th day of April, 1919.

SYDNEY NORTON BARUCH.
